SUBTERRANEAN STRUCTURE

Christian Gottwald, Cleveland Heights, Ohio,
assignor to The Ric-wil Company, Cleveland,
Ohio, a corporation of Ohio

Application November 30, 1934, Serial No. 755,314

6 Claims. (Cl. 138—48)

This invention relates to enclosures, and is particularly adapted to the formation of conduits and similar subterranean structures.

An object of the invention is to provide an improved structure in which the material will be efficiently distributed.

Another object is to provide an improved structure which may be easily constructed.

Another object is to provide an improved structure which will possess great strength.

Another object is to provide an improved structure which will effectively protect parts which it encloses from moisture.

Another object is to provide an improved structure which may be produced from a number of similar units or pieces.

Another object is to provide an improved structure having adjustable supporting means.

Other objects will hereinafter appear.

20 The invention will be better understood from the description of several practical embodiments thereof, illustrated in the accompanying drawings, in which;

Figure 1 is a transverse sectional view of one form of conduit embodying the invention and showing a plurality of pipes enclosed therein;

Figure 2 is a view similar to Figure 1 of another form of conduit, and illustrating an improved pipe supporting means;

30 Figure 3 is a fragmentary longitudinal sectional view taken on the line III—III of Figure 2;

Figure 4 is a transverse sectional view similar to Figures 1 and 2, but showing a third embodiment of the invention; and

Figure 5 is a fragmentary longitudinal sectional view taken on the line V—V of Figure 4.

In Figure 1 a conduit is shown consisting of a flat base 1 conveniently formed of concrete or similar material and provided with reinforcing such as bars 2, and above which is formed a substantially semi-circular or arch-shaped covering consisting of a plurality of similar arcuate tiles indicated generally at 3.

45 Within the space enclosed by the floor 1 and arch above mentioned are positioned a plurality of pipes, 4, 5 and 6 supported upon rollers 7 having trunnions 8 mounted in bearings formed on bifurcated standards 9 secured to the floor 50 or base as by bolts 10. The arch consisting of tiles 3 extends below the upper surface of the floor 1 into recesses 11 within which its ends are sealed as by cement 12.

Each tile is of generally quadrilateral shape 55 provided with dove-tail-shaped projections 13

on one edge and a dove-tailed recess 14 on its opposite edge.

The tile is of cellular structure, having an outer wall 15, an inner wall 16, and a central wall 17 between these two. It likewise has an end 5 18 carrying the dove-tail 13 and an end 19 into which is formed recess 14, while between these walls is a cross wall 20.

The tiles at the edges of the arch 21 are in effect equivalents of halves of the tiles 3 above 10 described.

The tiles are secured together by cement 22. The joints may be covered with caps 23 of cement and the entire exterior of the arch sealed with any desired waterproof material such as pitch 15 or other bituminous coating.

The space enclosed by the arch or roof and the floor may be filled with a loosely packed heat-insulating material 24, or the pipes may each be provided with solid heat-insulating coverings if desired.

It will be understood that, when intended for a subterranean conduit, this structure is built upon the bottom 25 of a trench, and that after the housing has been completed with the pipes, insulating material, and the like enclosed, the trench is filled in. Preferably the sides of the lower part of the trench, for an appreciable distance above the floor 1, is filled with material of rather large particles, such for instance as broken 30 stone 26, above which the trench is filled with the earth 27 which was removed in digging the trench.

It will be apparent that moisture accumulating within the conduits, or within the spaces within 35 the arch, will be drained into the recesses 28 of tiles 21 below the level of the upper surface of floor 1, and may be conveyed to any desired point of disposal.

While the arch above illustrated is of generally circular shape, it will be understood that the term "arch" is used to comprehend not only arcs of circles, but catenary, hyperbolic, parabolic and other arcs.

Figure 2 shows a modification of the apparatus 45 of Figure 1, in which the arched top has been flattened and supplemented with vertical sides. This structure consists of a base or floor 101, sides composed of generally rectangular tiles 121 each consisting of an outer wall 115, an inner 50 wall 116, an intermediate wall 117, a lower end 118, provided with a dove-tailed recess 114, an upper end 119 having a dove-tail-shaped projection 113, and a transverse wall 120.

The roof of this structure is shown as a series 55

of continuous slightly arched tiles or girders 103, each having an outer wall 130, an inner wall 131, two intermediate walls 132, and cross walls 133. The tiles of roof and walls are sealed to each other and to the floor by cement 122 and may be protected as above described in connection with the form of the first figure.

The disposal of the webs of the tiles, as well as the arch of the top, gives this structure, like that of Figure 1, a truss-like strength and rigidity against distortion both from the weight it supports and from lateral pressure.

A single U-shaped bracket 109 fits within the interior of the conduit, having supporting feet 110 resting upon the base 101, having slots 111 through its sides through which pass bolts 112 retaining bifurcated cradles 102, in which are supported ends of bars or rods 108 supporting rollers 107 on which rest pipes 104, 105 and 106.

As in the embodiment above described, drainage is effected through the unobstructed series of cells of the lowermost tiles 121, and any moisture accumulating within the conduit may reach these tiles by flowing along the space beneath the U-shaped brackets 109.

Figures 4 and 5 show a still further modification, in which the top arch or roof of the conduit has been still further flattened, so that it has become substantially a horizontal girder or slab. In these figures, the floor or base is indicated at 201 formed of concrete and upon which are supported walls consisting of cellular tiles 203. These tiles have inclined outer walls 215 so that the number of walls between these and the inner walls 216 increases from top to bottom, providing a structure of increasing strength as the supported weight and the pressure of the earth upon its sides increase. They also function in the manner of trusses to increase the strength of the structure.

The roof of this embodiment consists of a monolithic slab of concrete, conveniently formed by pouring this material upon a generally flat piece 217 of corrugated sheet metal resting upon the upper edges of tiles 203 and upon which the concrete forms a slab 218 embedding reinforcing means such as bars 219.

The portion of the floor 201 between the side walls consists of a thin layer of concrete 201a upon which are placed a plurality of hollow tiles 202, the concrete entering recesses between these and firmly binding them together. These tiles form a smooth paved surface on the top of the floor, and the hollows of the tiles being in alignment serve as additional drainage means, supplementing that provided by the cells in the lowermost blocks 203 and carrying away any moisture which may have entered the interior of the conduit.

Brackets 209 and rollers 207 similar to those described in conjunction with Figure 1 are used, and on these are supported pipes 204, 205 and 206.

Two of these pipes are shown as surrounded with heat insulating material, such as molded sectional coverings 220, which are protected

against friction with the rollers by metal shoes or plates 221.

While I have described the illustrated embodiments of my invention in some particularity, obviously many others will readily occur to those skilled in this art, and I do not therefore limit myself to the precise details shown and described, but claim as my invention all embodiments, modifications and variations coming within the scope of the subjoined claims.

I claim:

1. A built-up conduit consisting of a floor, a top, and sides, the sides comprising tile sections so constructed and arranged that the complete wall diverges outwardly from the top downwardly whereby a bracing effect is secured which tends to resist any lateral thrust to which the structure may be subjected.

2. A built-up conduit consisting of a floor, a top, and sides, the sides comprising tile sections so constructed and arranged that the complete wall diverges outwardly from the top downwardly whereby a bracing effect is secured which tends to resist any lateral thrust to which the structure may be subjected, and integral reinforcing inter-connecting webs within said tile sections.

3. A built-up conduit consisting of a floor, a top, and sides, the sides comprising tile sections so constructed and arranged that the complete wall diverges outwardly from the top downwardly whereby a bracing effect is secured which tends to resist any lateral thrust to which the structure may be subjected, and internal reinforcing cruciform webs integral with said tile sections and dividing the interior of said sections into a plurality of longitudinally extending hollows.

4. A built-up conduit consisting of a floor, a top, and sides, the sides comprising tile sections so constructed and arranged that the complete wall diverges outwardly from the top downwardly whereby a bracing effect is secured which tends to resist any lateral thrust to which the structure may be subjected, the sides each consisting of a plurality of superposed courses, the lower surface of each course being substantially co-extensive with the upper surface of the course therebelow.

5. A built-up conduit consisting of a floor, a top, and sides, the sides comprising hollow tiles each having a substantially horizontal bottom wall, a substantially horizontal top wall, and upwardly converging side walls whereby a bracing effect is secured which tends to resist any lateral thrust to which the structure may be subjected.

6. A built-up conduit consisting of a floor, a top, and sides, the sides comprising a plurality of courses of tile sections, each consisting of a horizontal bottom wall, a horizontal top wall and upwardly converging side walls, the side walls of each course of tiles being in alignment with those of adjacent courses whereby a bracing effect is secured throughout the entire extent of the sides which tends to resist any lateral thrust to which the structure may be subjected.

CHRISTIAN GOTTWALD. 65
